poration of New York

Application June 23, 1936, Serial No. 86,884

29 Claims. (Cl. 29—21)

This invention relates to a method and means for registering and trimming printing plates and more particularly stereotype or electrotype printing plates for multicolor and other printing in which accuracy of register is required.

Heretofore, in registering and finishing a set of printing plates to produce an image or design in multicolor, it has been a common practice to produce register or index marks on the marginal portion or "trimming margin" of the plate, which marks were located with respect to the matter on the plate and also an edge of the finished plate, so that after the margin was trimmed from the plate, all the plates of the set were registered with relation to a selected edge thereof. This method of registering the plates is satisfactory when all the plates of the set are of exactly the same size, and all the images or designs on the plates have the same dimensions and the image or corresponding portion thereof on each plate bears the same relation to the edge of the plate as the image or corresponding portion thereof in each of the other plates in the set. This desired accuracy is seldom attained, and, since each plate of the set of plates is registered with relation to one edge thereof, it is manifest that any inaccuracy in the plate or image dimensions will manifest itself in full dimension in a portion of the printed image.

Therefore, an object of this invention is to provide a method and means with which the conventional cruciform register marks or indices are located on the marginal portion or trimming margin of the plate but with accurate relation to the image, design, or matter on the plate and also with accurate relation to the center of the plate, and then trimming or cutting the four edges of the plate along lines located with respect to the register marks, and, consequently, the image and center of the plate, so that in registering a set of plates for producing a multicolor image or design, a given portion of the image or design on each plate of the set will be positioned with the same relation to its edges as the corresponding portion of the image or design on the other plates of the set. Consequently, any inaccuracy that may occur in the production of the finished plate will be reduced as much as one half, because the register of the plate is determined with relation to its center rather than a selected edge.

Another object of this invention is to provide a method and means with which the conventional register marks or indices are located on the trimming margin on the plate in accurate relation to the image or design thereon and also in accurate relation to the plate center, and notching opposed

margins of the plate at points located with accurate relation to the register marks and, consequently, the plate center and image or design, and then employing the notches to accurately locate the plate in a plate bending mechanism incorporating a novel plate receiving receptacle or holder. 5

A further object of this invention is to provide a method and means with which the conventional register marks or indices are located on the marginal portion of the plate in accurate relation to the image or design thereon and also in accurate relation to the plate center, or to a determined point adjacent the plate or image area center, notching opposed marginal portions of the plate at points located with accurate relation to the register marks and, consequently, the plate center and image or design, employing the notches to accurately locate the plate in a plate bending machine to bend the plate to arcuate or semi-cylindrical form, and then employing the notches in 10 locating the arcuate plate in accurate axial relation on the saddle of a plate trimming mechanism. 15

Another object of this invention is to provide a method and mechanism with which the conventional register marks or indices are located on the marginal portion of the plate in accurate relation to the image or design thereon and also in accurate relation to the plate center, or determined adjacent point, notching opposed marginal portions of the plate at points located with accurate 20 relation to the register marks and, consequently, the plate center and image or design, employing the notches to accurately locate the plate in a plate bending machine to bend the plate to arcuate or semi-cylindrical form, and then employing the notches in 25 locating the arcuate plate in accurate axial relation on the saddle of a plate trimming mechanism. 30

Another object of this invention is to provide a method and mechanism with which the conventional register marks or indices are located on the marginal portion of the plate in accurate relation to the image or design thereon and also in accurate relation to the plate center, or determined adjacent point, notching opposed marginal portions of the plate at points located with accurate 35 relation to the register marks and, consequently, the plate center and image or design, employing the notches to accurately locate the plate in a plate bending machine to bend the plate to arcuate or semi-cylindrical form, and then employing the notches in 40 locating the arcuate plate in accurate axial relation on the saddle of a plate trimming mechanism, and adjustably locating and locking the arcuate printing plate circumferentially on the saddle with relation to the register marks, and, consequently, the center of the plate, and then trimming the four edges of the plate along lines 45 located with relation to the plate design and center of the plate. 50

It is an object of my present invention to provide an improved electrotype or stereotype printing plate finishing mechanism of generally improved construction, whereby the device will be simple, durable, accurate, and inexpensive in construction, as well as convenient, practical, serviceable and efficient in its use.

With the foregoing and other objects in view, which will appear as the description proceeds, the invention resides in the combination and arrangement of parts, and in the details of con- 55

struction hereinafter described and claimed, it being understood that various changes in form, proportion, and minor details of construction may be made within the scope of the claims without departing from the spirit or sacrificing any advantages of the invention.

For a complete disclosure of the invention, a detailed description of an improved method and mechanism for registering and finishing stereotype or electrotype printing plates will now be given in connection with the accompanying drawings forming a part of the specification, wherein:

Figure 1 is a side elevation of the plate notching mechanism, portions being broken away;

Figure 2 is a similar view showing the upper portion of the plate notching mechanism, but with its components depicted in a different operating position;

Figure 3 is a plan view of the plate notching mechanism, parts appearing in section, the direction in which the view is taken being indicated by the arrow 3 in Figure 2;

Figure 4 is a fragmental end view of the plate notching mechanism, portions being broken away, the direction in which the view is taken being indicated by arrow 4 in Figure 1;

Figure 5 is a vertical sectional view of the plate bending mechanism, parts being broken away;

Figure 6 is a fragmental plan view of the flexible plate holder and notched plate, the view being taken in the direction indicated by the arrow 6 in Figure 5;

Figure 7 is an end elevation of the improved plate trimming mechanism;

Figure 8 is a longitudinal vertical sectional view taken on the line 8—8 of Figure 7, portions being broken away;

Figure 9 is a fragmental vertical transverse sectional view taken on the line 9—9 of Figure 8;

Figure 10 is a fragmental elevation, parts appearing in section, the view being taken in the direction indicated by the arrow 10 of Figure 9;

Figure 11 is a fragmental longitudinal vertical sectional view, parts appearing in elevation, depicting the mounting for the plate-supporting saddle and plate-locating and adjusting mechanism;

Figure 12 is a substantially horizontal transverse sectional view taken on the line 12—12 of Figure 8;

Figure 13 is a fragmental detailed plan view of a plate-trimming saw supporting mechanism, the view being taken in the direction indicated by arrow 13 in Figure 7;

Figure 14 is an elevational view of a portion of the printing plate, the removed trimming margin being indicated in dotted lines;

Figure 15 is a detailed transverse sectional view, parts appearing in elevation, depicting the relative position of the printing plate, plate locating and adjusting lever, and the trimming saw for removing the straight axial margin from the plate;

Figure 16 is a fragmental end elevation of a modified plate-trimming mechanism;

Figures 17a, 17b, 17c, 17d and 17e are diagrammatic views depicting the various stages in my improved method for finishing printing plates;

Figure 18 is a diagrammatic view depicting the relative positions of images or image components in superposed plates of different sizes where the registering relation of the plates is determined

with relation to an edge or edges of the plates, and

Figure 19 is a similar view depicting the relative positions of images or image components in superposed plates of different sizes where the registering relation of the plates is determined with relation to a determined point located at or near the center of the plate.

Referring to the drawings in which similar reference characters designate corresponding parts, there is depicted a mechanism for notching, bending and trimming electrotype or stereotype printing plates, and this mechanism may be incorporated in a single frame, or, if desired, the mechanism for carrying out my invention may be supported by separate frames. It is to be understood, however, that the disclosed invention is directed to mechanism and method for trimming stereotype or electrotype printing plates so that the finished edges of each plate will accurately bear definite relation to the center of the plate and also the design or printing matter appearing thereon.

Plate notching

Referring to Figures 1 to 4, there is depicted a mechanism for carrying out a phase of my invention, which mechanism includes a frame 20 having a bracket or platform 21 bolted or suitably secured thereto, and spaced levers 22 are rigidly secured to a transversely extending shaft 23 rotatably supported in bearing ears or lugs 24 extending downwardly from the platform 21. The intermediate portion of each lever 22 is pivotally connected with the lower terminal of a link 25, as indicated at 26, and the upper terminal of each link 25 is pivotally connected to a lever plate 27, as indicated at 28, and the lever plate 27 is in the form of a relatively broad flat member, as best seen in dotted outline in Figure 3. In order to insure that the lever plate 27 is rigidly supported to move about a horizontal axis, one terminal of this lever 27 is pivotally secured to fixed lugs 30, as indicated at 31, upstanding from the platform 21 at spaced points, and best seen in Figures 1 and 3. The outer terminal of the lever plate 27 is pivotally secured at opposed points, as indicated at 32, to ears or brackets 33, which extend downwardly from a plate-supporting table 35, as best shown in Figures 1 to 3. Spaced links 36 are pivotally secured to ears 34 which extend downwardly from a portion of the table 35 which is remote from the ears 33, and the lower terminal of each link 36 is pivotally secured to a lever 22 by bolts or other suitable securing device, as indicated at 37. One of the levers 22 extend outwardly beyond its pivot 31, and is pivotally secured to a link 38, as indicated at 40, and the lower terminal of the link 38 is operatively secured to a treadle 41 pivotally supported, as indicated at 42, by a bracket 43 upstanding from the machine frame 20. Inasmuch as the construction of the treadle is of conventional and well known form, the connection between the lower terminal of the link 38 and the treadle 41 is not illustrated except for the illustration given in Figure 1. A rod 44 is pivotally secured to the lever plate 27, as indicated at 45, and the lower terminal of this rod extends through an aperture 46 formed in the machine platform 21, so that the rod 44 is slidably received therein. In order to bias the plate lever 27 upwardly or away from the platform 21, a helical spring 47 is positioned on the rod 44, and its opposed terminals

60
65
70
75

engage the platform 21 and a collar 48 carried by the rod 44.

From the foregoing it is manifest that by depressing the treadle 41, the link 38 is moved downwardly, thereby moving the levers 22 downwardly about their fulcrum 23. As the outer terminal of each lever 22 moves downwardly, it pulls downwardly on the links 36 and the table 35. The downward movement of the levers 22 also moves the links 25 downwardly, which, in turn, move the lever plate 27 downwardly about its fixed fulcrum 31 against the tension or bias of the spring 44. As the outer terminal of the plate lever 27 moves downwardly, it also pulls downwardly on the ears 33 and table 35, and by referring to Figures 1 and 2, it will be seen that the leverage ratios in the levers 22 and 27 are so proportioned that as the levers 22 move downwardly about their fixed fulcrum 23, and the lever 27 moves downwardly about its fixed fulcrum 31, the table 35 is moved downwardly so that it is maintained in substantially horizontal position throughout the amplitude of its movement. When the treadle 41 is released, the spring 47 forces the components of the table actuated mechanism upwardly, thus returning the plate to its uppermost position, and the reason for moving the table upwardly and downwardly in a horizontal position will be hereinafter disclosed.

It is well known and understood by those skilled in the art that each plate in a series of printing plates for producing a multicolor image or design is suitably marked with register indices to aid in trimming the plate in order to obtain accurate registration of the superposed colors in producing the multicolor image. These register indices are usually cross marks positioned in the marginal portion of each plate, and are located with relation to an edge of the plate or design or printed matter appearing thereon. Applicant produces the usual cruciform register marks or indices M on the marginal portion of the plate P, as shown in the diagrammatic Figures 17a and 17b, but these marks are located with relation to a predetermined point on the plate or the center of the plate and the matter appearing on the plate. Therefore, since the register marks or indices are located with relation to the center of each plate, and the plate then trimmed along lines located with relation to the register marks, and, consequently, center of the plate, it is manifest that the four finished edges of the plate will be accurately located relative to the center of the plate as well as the images thereon. Any preferred means may be resorted to for producing and locating the register indices M in the marginal portions of the plate, but a convenient method is found in placing cruciform register marks M in the longitudinal margins of the plate at points coinciding with a line passing transversely through the center of the plate, and also positioning a cruciform mark M in the transverse or side margin of the plate at a point coinciding with a line passing longitudinally through the center of the plate, as best shown in Figure 17a. Thus it is seen that although the cruciform register marks or indices M are positioned in the trimming margin of the plate, they have been located with relation to the center of the plate, for reasons to be hereinafter more fully disclosed.

Spaced magnifying glasses or microscopes 50 of conventional design are supported by brackets 51 secured to and upstanding from the frame 52 or platform 21. These magnifying glasses, as

will be hereinafter disclosed, are employed to sight and locate the register indices, so that the printing plate P may be properly located on the table 35, and, in most instances, two glasses will suffice to properly locate the plate. In Figures 1 and 2 of the drawings, two glasses have been illustrated, although it is to be understood that, if desired or required, three glasses may be provided, the third glass being employed to sight the register marks formed on the transverse edge of the plate. The magnifying glasses 50 have been depicted in the accompanying drawings as being supported by fixed brackets 51, but, it is to be understood, that in order to accommodate different size plates, the glasses 50 may be supported by adjustable brackets which may be adjusted to move the glasses towards the center of the table 35 when smaller plates are employed. Each corner of the table 35 is provided with two upstanding lugs 52 disposed at right angles to each other and having threaded apertures formed therein for the reception of threaded adjusting screws 53. By this arrangement two adjusting screws engage each corner of the plate P, and by manipulating the enlarged knurled heads 55 of the screws 53, the plate P may be adjustably moved on the table 35 until the cruciform register indices thereon align with the hair line sighting marks or indices provided in the microscope or magnifying glasses 50, and when these register indices of the plate and hair line marks are in proper register or alignment it is then known that the plate is accurately positioned on the table in definite relation to its register marks, and, consequently, the center of the plate or selected point on the plate.

A rotary cutter or saw 56 is secured to a shaft 57 rotatably mounted in suitable bearings 58 supported by the machine platform 21. A saw 56 is located adjacent each end of the table 35, and the table is provided at each end with a slot 60 to permit the saw to pass therethrough, for reasons to be hereinafter disclosed. A pulley or sprocket 61 is secured to the outer terminal of each shaft 57, and a chain or belt 62 is trained around each pulley or sprocket. The lower portions of the chains or belts 62 are trained around drive pulleys or sprockets 3, best shown in Figures 1 and 2, and these drive pulleys or sprockets are operatively supported on a shaft 63 which is driven by electric motor 64, best shown in Figures 1 and 3. In order that the saws or cutters 56 may operate in opposed directions or sense, one of the belts or chains 62 is crossed, so that the saw 56 appearing at the left of the machine is rotated in a counter-clockwise direction, and the saw at the right of the machine is rotated in clockwise direction. The saw-driving mechanism may be suitably housed for the protection of the operator, but, inasmuch as such housing mechanism is common and well known to those skilled in the art, it is not here illustrated.

In order to protect the operator from injury by the cutters and to guard against flying chips striking the magnifying glasses, guards 67 are provided and are secured to members 68 which are loosely journaled on the shafts 57. The members 68 are provided with arms 69 secured to and extending downwardly from each of the guards 67, as best shown in Figures 1 and 2. Brackets 70 extend downwardly from the table 35, and each bracket has a roller 71 rotatably supported in its outer or lowermost terminal for cooperative engagement with the arm 69, so that as the table 35 is lowered the rollers 71 force the arms 69 out-

wardly, thereby rocking the saw guards 67 over the saws, the saw guards 68 being counterweighted to maintain the arm 68 in engagement with the rollers 71.

In the operation of the plate notching mechanism the plate P is placed upon the table 35, and then the plate adjusting screws 53 are manipulated until the cruciform register indices M marked on the plate are moved to accurate alignment with the hair line sighting indices provided in the magnifying glasses or microscopes 50. After the plate P has been accurately positioned on the table 35 by means of the microscope and adjusting screws 53, these screws are tightened to maintain the plate in this position, and then the treadle 41 is depressed. As the treadle 41 moves downwardly, the plate P moves downwardly into engagement with the rotating saws 56, thereby cutting register or locating notches 72, best shown in Figures 6 and 17b, in opposed edges of the plate, and these notches are located in accurate relation to the register marks of the plate, and, consequently, the plate center.

It is now manifest that the plate has been notched in accurate relation to its register indices, plate center, and matter appearing on the plate, so that these notches may be employed in other phases of my invention to produce an accurately finished plate, as will be hereinafter disclosed.

30 Plate bending

After the locating or register notches 72 have been formed in the plate P, the plate is then positioned, as shown in Figures 5 and 6, in a plate-receiving receptacle or holder 73 having a flexible sheet metal backing 75 and marginal flange 76. The plate holder 73 is shaped to receive the plate P, and this holder is provided at its leading end with a fixed arcuate stop member or block 77, which is rigidly secured to the backing 75, by screws or other suitable securing devices 78, and a yieldable arcuate stop member 80 is slidably secured to the opposed or trailing terminal of the plate holder 73 by screws or rivets 81, which extend through slots 82 formed in the yieldable stop 80 and are secured to the backing 75. In order to bias the yieldable stop member 80 towards the leading terminal of the plate holder 73, leaf springs 83 are suitably secured to the yieldable stop 80 and engage the rear flange 76. When the plate P is positioned in the plate holder 73, its notches 72 are engaged by tongues or projections 85 formed on the fixed and yieldable stop members 77 and 80, respectively, thus accurately positioning the plate P in the holder 73 preparatory to its bending operation. The plate-bending mechanism, shown in Figures 5 and 6, includes a relatively large roller 86 rotatably supported by a frame 84, and two spaced cooperating smaller rollers 87 are rotatably mounted in a carriage 88, which is slidably mounted in a bracket 90 supported by the frame 84. The rollers 86 and 87 are arranged in conformity with the conventional three-roll plate benders, and the small rollers 87 may be adjusted relative to the large roller 86 by an adjusting screw 91 which is swiveled in the bracket 90 and threadedly engages the carriage 88, so that by rotating the screw, the rollers 87 may be moved towards or away from the large roller 86 to properly accommodate the plate and its holder. An arcuate or spirally-shaped plate-supporting or receiving bracket 92 is secured to the machine frame 84, and its plate-supporting portion defines an arc of greater radius or radii 75 than the periphery of the bending roller 86. A

table or platform 74 is secured to the frame 84, and is positioned to support the plate holder 73 in its initial or plate receiving position. The roller 86 is driven from any suitable source of power, not shown, in conformity with the usual practice, and as this roller is rotated counterclockwise, the plate P and holder 73 are moved forwardly between the rollers 86 and 87, thus bending the plate P into arcuate or semicylindrical form, so that its notches 72 appear in the straight axial edges thereof. When the plate P and holder 73 have moved forwardly between the rollers 86 and 87 sufficiently to bend the plate to desired shape, the driving mechanism is stopped by a conventional limit switch or stop mechanism, not shown, so that the plate is supported between the roller 86 and bracket 92 in position to be conveniently removed from the machine.

By this arrangement the fingers 85 of the fixed and yieldable stop members 77 and 80 engage the notches 72 of the plate P, thereby accurately locating the plate in the receptacle or holder 73 to insure the accurate bending of the plate with its notches 72 positioned in the straight axial edges of the bent plate, and, since the notches 72 have been located with relation to the register indices, it is manifest that these notches may be employed in the trimming operation to aid in locating the bent plate in the trimming mechanism, as will be hereinafter more fully disclosed. 30 Since the notches 72 are accurately located with relation to the register indices marked on the plate P, the engagement of the tongues 85 with the notches 72 align the plate in its holder 73, so that the longitudinal edges of the plate are 35 perpendicular to the axes of the bending rollers 86 and 87, consequently, assuring that after the plate is bent, its notches 72 will be positioned in edges that are disposed in accurate axial relation to the arcuate plate. 40

Plate trimming

In order to accurately trim or shape the plate P after it has been notched and also bent to semi-cylindrical form to conform to the printing cylinder periphery, a trimming mechanism, best shown in Figures 7, 8, 9, 10, 11, 12, 13 and 15, is provided, and it includes a frame 95 of any preferred configuration to best support the operating components of the device, and a cylindrical shell or tube 96 extends longitudinally of the machine frame 95 and is rotatably supported in spaced antifriction bearings 97 and 98 suitably supported by the machine frame, the bearing 98 may also serve, in a measure, as a thrust bearing to prevent longitudinal movement of the shell 96 relative to the machine frame 95. An arcuate or semi-cylindrical saddle 100 is supported by the machine frame intermediate its ends, and the outer surface of this saddle preferably has the same diametrical dimension as the outer surface of the plate cylinder of the printing press, for reasons to be hereinafter disclosed. Spaced antifriction bearings 101 are positioned in the shell 96, as shown in Figure 8, to rotatably support a shaft 102 which extends axially through the shell 96, and a worm wheel 103 is keyed or otherwise secured to the outer terminal of the shell 96, as best shown in Figure 8 of the drawings. A worm 105 extends transversely of 70 the machine and is rotatably supported in spaced antifriction bearings 106, best shown in Figure 7. This worm 105 is driven from an electric motor 107 through a sprocket or pulley 108 secured to the shaft of the worm 105, a sprocket or pulley 75

110 secured to the shaft of the motor 107, and a chain or belt 111 which is trained around the sprockets 108 and 110, the motor 107 being suitably secured to and supported by the machine frame, as shown in Figures 7 and 8. Gear teeth are cut into spaced portions of the shaft 102, as best shown in Figure 8, to define drive pinions 112, and each pinion 112 meshes with a gear 113 rotatably mounted in antifriction bearings 115 carried by a supporting housing 116. A shaft 117 is operably mounted in each housing 116, as best shown in Figure 8. One end of each shaft 117 is rotatably mounted in twin ball bearings which function as both radial and thrust bearings, and the opposed end of the shaft is rotatably mounted in roller bearings 119. A pinion 120 is secured to each shaft 117 and meshes with the gear 113, so that, as the shaft 102 is rotated, power is imparted to each shaft 117 through the pinion 112 and gears 113 and 120. A beveled circular cutter or saw 121 is secured to the outer terminal of each shaft 117 for engagement with the arcuate circumferential edges of the printing plate P, as will be more fully disclosed hereinafter. Each housing 116 is secured to and moves with the cylindrical shell 96, so that, as the shell 96 is rotated about its axis, the housing 116 moves in an arcuate path of travel about the axis of the shell 96, so that the circular cutters 121 will follow the circumferential arc of the plate P. Therefore, when the motor 107 is energized, it imparts power to its sprocket or pulley 110, belt or chain 111, sprocket or pulley 108, worm 105, and worm wheel 103, thereby rotating or oscillating the casing 98 and housing 116, so that the circular cutters 121 accurately trim the arcuate margins from the plate to produce accurately located arcuate beveled edges, as will be more fully disclosed hereinafter. While the cutters 121 and their supporting housing 116 and the cutter driving mechanism are depicted in Figures 7 and 8 as being in the upright intermediate position, it is to be understood that this is the position occupied by these components when the cutting operation is approximately half finished, and that their normal inoperative position is at a lower portion of their arcuate path of travel, at a point where the circular cutters 121 are not in engagement with the arcuate printing plate positioned on the saddle 100. In order to drive the shaft 102 to thereby impart motion to the circular cutters 121, an electric motor 122 is supported by the machine frame, as best shown in Figure 8, and this motor imparts power to the shaft 102 through a grooved pulley 123 carried by the shaft of the motor 122, and a grooved pulley 125 secured to a reduced extension 126 of the shaft 102, and preferably V-shaped belts 127 which are trained around the pulleys 123 and 125. Although belts and pulleys have been shown for imparting power from the motor 122 to the shaft 102, it is, of course, to be understood that chains or sprockets or other suitable power imparting instrumentalities may be employed.

In order to adjust the notched semi-cylindrical printing plate P upon the saddle 100 to insure the proper location of the plate relative to the marginal trimming cutters or saws, preparatory to cutting or trimming the margins from the plate, the plate is first placed on the saddle 100 and positioned so that each notch 72 formed in its straight axial edge is engaged by an alining finger or lug 128, formed at the free or outer terminal of a lever 130, which is fulcrumed to a

bracket 131, secured to the saddle 100, there being a lever 130 positioned adjacent each axial edge of the plate P, as best shown in Figures 7 and 17c of the drawings, and one of the levers 130 is shown in detail in Figure 15. The outer terminal of a toggle link 132 is pivotally secured to each lever 130, as best shown in Figures 7 and 11, and the opposed terminals of the toggle links 132 are pivotally united and secured to a lever link 133, as indicated at 134, and the intermediate portion of the lever link 133 is pivotally secured to a lever arm 135, as indicated at 136. One terminal of the lever arm 135 is fulcrumed to the machine frame or any convenient bracket thereof, as indicated at 137, and its opposed or movable terminal is pivotally secured to a rod or link 138, as indicated at 140. The lower terminal of the rod or link 138 is pivotally secured to a treadle 141, as indicated at 142, and the treadle, in turn, is fulcrumed to the machine frame, as indicated at 143, and shown in Figure 7 of the drawings. A shaft 145 extends longitudinally of the machine frame and is rotatably mounted in suitable bearings 146 carried by the frame, as best shown in Figures 7, 8 and 11 of 25 the drawings. The outer terminal of this shaft has an operating handle 147 secured thereto, and its intermediate portion has an arm 148 keyed or otherwise rigidly secured thereto, and the outer terminal of the arm 148 is pivotally secured to a link 150, as indicated at 151. This link 150, in turn, has its opposed terminal pivotally secured to the lower end of the lever link 133, as indicated at 152.

In order to move the locating fingers or lugs 128 of the levers 130 into engagement with the registering or locating notches 72 of the printing plate P, the treadle 141 is depressed, thereby moving the link 138 and lever arm 135 upwardly. The upward movement of the lever arm 135 about its fulcrum 137 moves the lever link 133 upwardly, thereby imparting upward and outward movement to the toggle links 132, which, in turn, swing the levers 130 upwardly about their fulcrums until their locating fingers 128 enter the notches 72 of the printing plate P. When the locating fingers 128 engage the notches 72, the plate is then positioned in correct axial relation on the saddle 100.

After the plate has been placed on the saddle 100 and correctly positioned axially by the engagement of the locating fingers 128 with the notches 72 of the plate, the plate may then be temporarily held on the saddle by a mechanism which includes a bell crank lever 153 having a manipulating handle 155, and the lever 153 is fulcrumed to a plunger rod 156, as indicated at 157. An enlarged head 158 is formed on or secured to the rod 156, and the shank 160 of a cushioned shoe 161 is secured to the head 158 by a tubular nut 162 which clamps a ball or enlargement 163 formed on the inner terminal of the shank within a socket formed in the enlarged head 158. The cushioned shoe 161 is normally biased towards the saddle 100 by a helical spring 165 which surrounds the rod 156, and one terminal of the spring engages the enlarged head 158 and its opposed terminal engages the end wall of the cylindrical housing 166 in which the rod 156 and enlarged head 158 are slidably mounted. When the handle 155 is moved downwardly to the position shown in Figures 8 and 10, the spring 165 forces the cushioned shoe 161 into engagement with the printing plate P, and exerts suffi- 75

cient stress against the plate to hold it on the saddle 100.

In order to position the plate P in accurate relation circumferentially of the saddle, the handle 147 is moved thereby rocking the shaft 145, which, in turn, moves the arm 148 about the fulcrum shaft 145. The movement of the arm 148 imparts movement to the link 150, which, in turn, rocks the lever 133 about its fulcrum 136, thereby moving one of the levers 130 downwardly and the opposed lever 130 a corresponding distance upwardly, thus rocking or adjustably moving the plate P circumferentially on the saddle 100.

While the plate P is being adjusted circumferentially on its saddle 100, the treadle 141 may be depressed, thus causing the levers 130 to press upwardly against the axial edges of the printing plate P, to oppose the pressure of the cushioned shoe 161, thereby slightly lifting the plate P from the saddle 100 thus permitting the plate to be more easily moved circumferentially on the saddle. In order to accurately position the plate P circumferentially on its saddle 100, a magnifying glass or microscope 167, shown in Figure 8 of the drawings, is employed to observe the position of the register mark M positioned on an arcuate margin of the plate P, and, in sighting the register mark M through the microscope or magnifying glass 167, the circumferential component of the cruciform register mark M is not considered, but the axial component is accurately aligned with the hair line in the microscope, thus accurately indicating the correct circumferential position of the plate P on the saddle 100.

After the plate has been accurately located, both axially and circumferentially, on the saddle 100, it may be securely clamped to the saddle by a mechanism, best shown in Figures 7, 8, 9 and 10. This mechanism includes a transversely extending shaft or rod 168 which extends through a slot 170 formed in the enlarged plunger head 158, and a suitable manipulating wheel or handle 171 is secured to each terminal of the shaft 168. Portions of the shaft 168 adjacent the hand wheels 171 are threaded, as indicated at 172, and these threaded portions of the shaft extend through nuts 173 pivotally secured to the outer arms 174 of bell crank levers 175 which are fulcrumed on spaced shafts 175' supported by brackets 95 forming components of the machine frame 95. Each bell crank lever 175 has spaced diversion arms 176, and the innermost terminals 177 of the arms 176 are provided with aligned bores or apertures for the reception of a stub shaft 178. The opposed terminals of each stub shaft 178 are received within and suitably secured to bosses 180 formed on the outer terminals of flanges 181 extending upwardly from an arcuate clamping foot 182. Felt or other suitable cushioning material 183 is positioned on the inner arcuate face of each clamping foot, and is secured thereto by suitable clamping bars or straps 184 received within grooves formed in the arcuate face of the foot 182, and these clamping bars 184 are secured to the foot by flat-headed screws 185 so that the bars securely bind the felt strap to the foot. The marginal portions of the felt cushion is clamped to the edges of the foot by suitable clamping bars or straps 184'. In order to yieldingly maintain the components of the plate clamping mechanism in predetermined position, spaced helical springs 186 surround the unthreaded portion of the rod or shaft 168, and one terminal of each spring engages a collar 187 suit-

ably secured to the rod 168, and the opposed terminal of each spring 186 engages the enlarged plunger head 158, as best shown in Figure 9. The springs 186 exert equal stress in opposed directions on the rods 168, thus maintaining the components of the clamping device in predetermined relation to the plate supporting saddle 100. When it is desired to securely clamp the printing plate P on the saddle 100, the convenient one of the hand wheels 171 is manipulated to rotate the shaft 168. The rotation of the shaft 168 causes the nuts 173 to feed outwardly along the shaft, thereby causing the bell cranks 175 to move the clamping feet 182 into engagement with the outer surface of the printing plate P, thus securely binding the plate in correct position on the saddle. If one clamping foot 182 engages the plate P in advance of the other, then a spring 186 will yield to permit the rod to impart equal stress to both feet 182 through the interposed bell cranks 175.

After locking the plate P on the saddle, all four edges thereof may then be cut or trimmed to accurate predetermined dimensions to produce beveled edges to be engaged by suitable plate clamps carried by the printing cylinder, as will be hereinafter more fully disclosed. In trimming the arcuate edges of the plate, the motors 107 and 122 are energized, thus driving the circular cutters 121, and also moving the cylindrical shell 96 and saw supports or housing 116 about the axis of the shaft 102, which also coincides with the axis of the semi-cylindrical plate supporting saddle 100, thus causing the saws 121 to travel in accurate paths coinciding with the arcuate edges of the supported plate to cut away the marginal portions of the plate and produce arcuate beveled edges which are accurately located relative to the center of the plate.

In order to trim the straight axial edges of the plate, cutting or sawing, and supporting mechanism therefore, is provided, which mechanism includes a rail 188 supported at each side of the machine frame 95 by brackets or braces 190, best shown in Figures 7 and 13 of the drawings. Each rail 188 extends longitudinally of the machine, and its upper and lower longitudinal edges are machined to define opposed accurately-dimensioned guideways or tracks 191. A saw or cutter supporting carriage 192 is provided for movement longitudinally along each rail 188, and each carriage includes a substantially U-shaped frame 193 which extends partly around each rail 188, and spaced rollers 195 are rotatably secured to the frame 193, by screws or other suitable securing or supporting means 196, to engage the upper and lower horizontal edges of the guideways or tracks 191, and similar spaced rollers 197 are rotatably secured to and supported by the frame 193 on short shaft members or screws 198, which rollers engage the vertical machine surfaces of the tracks 191 at points adjacent their upper and lower terminals. By this arrangement the carriage 192 is mounted for free movement along the tracks 191 of the rail 188, and inasmuch as the tracks 191 and cooperating rollers 195 and 197 are accurately machined to close tolerances, the carriage 192 will move accurately in parallelism with the axis of the plate supporting saddle 100 and supported plate P. An electric motor 200 is suitably secured to a supporting block 201 which is mounted for vertical sliding movement in each carriage frame 193 by means of guide extensions 202 slidably received in vertical guideways 203 formed in the carriage frame.

Each electric motor 200 drives a beveled saw or cutter 205, as best shown in Figures 7, 8 and 13, and in order to adjustably move the saw or cutter 205 vertically relative to its carriage 192, and consequently the plate supporting saddle 100, an adjusting screw 206 is swiveled in a boss 207 extending inwardly from each carriage frame 193, and the lower terminal of each screw 206 is threaded in a motor supporting block 201, as indicated at 208, and best seen in Figure 7 of the drawings. Inasmuch as the adjusting screw 206 is swiveled in the lug 207 and held against longitudinal motion relative thereto, it is manifest that by rotating the adjusting screw 206, the motor supporting block 201, motor 200 and saw 205 are moved vertically, so that the saw 205 is brought into accurate relationship with the straight axial margin of the printing plate, for reasons to be hereinafter set forth. After each saw 205 has been correctly adjusted relative to an axial margin or edge of the printing plate, its motor-supporting block 201 may be locked against movement relative to the carriage frame 193 by a screw 210 which extends through an aperture formed in the carriage frame 193 and is threaded into the motor supporting block 201, as best seen in Figures 7 and 13 of the drawings. In order to gain access to each screw 210, an aperture 211 is formed in the rail 188, so that a wrench or other suitable tool may extend therethrough for engagement with the head of the locking screw 210.

It is preferable to move the cutters or saws 205 and their drive motors 200 relatively slow along their path of travel during the cutting operation, and to return them to their original or starting position at an accelerated speed. This is accomplished by the provision of a driving mechanism which includes a relatively large gear 212 rotatably supported on antifriction bearings 214 supported in a housing 213 carried by the machine frame 95, and a pinion 215 meshes with the gear 212, the pinion being driven by an electric motor 216, best seen in Figure 7 of the drawings, and the pinion 215 is rotatably mounted in antifriction bearings supported by the housing 213, as best shown in Figure 12. A lever arm 217 is keyed or otherwise secured to a shaft 218 which extends transversely across the machine and has a relatively long arm 220 keyed or otherwise secured to each terminal, so that the lever arm 217, shaft 218 and long arms 220 move about the axis of the shaft 218 in unison. The arm 217 is provided with an elongated guide opening or slot 221, as best seen in Figure 12 of the drawings, and an accurately machined guide way or surface 222 is formed at each side of the slot 221 and extends longitudinally thereof. A spindle or stub shaft 23 is suitably secured to the gear 212 by a nut or other suitable securing device 225, and spaced antifriction bearing members 226 are carried on the stub shaft 223 and arranged so that one bearing member engages each guide way 222. A link 227 is pivotally secured to the outer terminal of each arm 220, and the opposed terminal of each link 227 is pivotally secured to a carriage frame 193, so that movement of the arms 220 will cause the carriages 192 to move along the supporting rails 188.

In trimming the straight axial edges of the plate P, the motor 216 is energized, and this motor drives the pinion 215 which rotates the gear 212, and, as the gear 212 rotates, an antifriction member 226, by engaging a guide way 222 of a slot 221, causes the lever arm 227 to rock in a

counterclockwise direction, as viewed in Figure 8. As the arm 217 moves, corresponding movement is imparted to the arms 220, which, in turn, draw the saw-supporting carriages 192 along the guide tracks 191 of the supporting rail 188, thereby moving the spaced saws or cutters 205 along the opposed straight axial margins of the plate, so that these margins are trimmed from the plate to produce accurately located beveled edges for engagement with suitable plate clamping means when the plate is clamped in printing position on the form cylinder of the printing machine. In advancing the saws or cutters 205 during their cutting operation, an antifriction member 226 engages a guide way 222 of the arm 217 during the advancing movement of the large gear 212 through an arc of travel greater than 180°, and through an arc of travel less than 180° during the idle return movement of the saws. Thus it is manifest that the saws 205 are advanced relatively slow during their cutting operation, and that their return movement is accelerated.

In order to insure safety of operation and also maintain definite sequence of operation of the various operating components of the plate trimming mechanism, electric interlocks of conventional form may be provided so that the motors can not be started until the plate is locked in position on the saddle 100, and the locating members are disengaged. This interlocking system may also include limit switches to stop the motors when the cutting cycle is completed, and the circuits may be interlocked to avoid interference between the cutters which cut the straight axial edges of the plate and those which cut the curved circumferential edges. Inasmuch as electrical interlocks of this type are well known and understood by those skilled in the art, and are not a specific part of this invention, they have not been illustrated.

From the foregoing it is manifest that applicant has provided method and means for producing a set of printing plates for multicolor or other printing in which each plate will be identically the same size as the other plates in the set, and, in which, the image will bear the same relation to the edges of the plate as all plates of the set. Applicant has also provided method and means for locating the conventional register marks relative to the center of the plate, and then accurately finishing the entire plate with relation to its center so that any errors or inaccuracies due to variation in plate bending or matrix shrinkage or other causes will be only one half as great as where the registering is done from an edge or a point near the edge of the plates, which was a common practice prior to my invention.

In employing these plates in printing, it is intended to provide printing cylinders with individually adjustable clips to engage all four edges of the plate, and the clips for two adjacent edges will be marked with relation to the cylinder, so that the mark on the cylinder and on the clip will be in alignment when a perfect plate is clamped in accurate register. By this means, assuming that the work has been properly done, it will be possible to "plate" a printing machine by properly pre-setting the marked clips, and, then, by simply tightening clips against the two edges of the plate that do not engage the pre-set clips, all the plates to be in perfect register, but, however, if there has been an error somewhere in the process, any of the

clips may be moved to move the plate as desired. Inasmuch as this arrangement of plate clips will readily manifest itself to those skilled in the art and is not a specific element of my present invention apart from the method and mechanism disclosed, the plate clip arrangement is not illustrated.

In Figure 16 a modified plate trimming mechanism is disclosed, which is similar to the device depicted in Figures 7 and 8, but which is constructed and arranged to accurately position a semi-cylindrical printing plate upon its semi-cylindrical saddle 100 without forming notches in the straight axial edges of the plate P. Its plate adjusting levers 130a are similar to the levers 130 except the notch engaging fingers or lugs have been omitted so that the outer terminals of the levers 130a engage the straight axial edges of the plate, thereby movably adjusting the plate P on the saddle 100, so that it may be accurately located circumferentially on the saddle by observing the register mark formed on the curved margin of the plate in the manner hereinbefore disclosed. Inasmuch as the register or locating notches are not formed in the axial edges of the printing plate P, it is necessary to correctly position the plate axially on the saddle by observing register marks or indices produced thereon. In this form, the plate is provided with register marks M in its margins at the center of the top of the plate and at the center of the bottom and also at the center of one side. These marks may be the usual cruciform marks M, shown in Figure 17a, or they may be simply straight lines, which, if projected, would cross at the center of the plate. In locating the plate axially on the saddle 100, two magnifying glasses or microscopes 230 are provided, and these glasses are supported by brackets 231 suitably secured to the machine frame. Each magnifying glass 230 is positioned so that its sighting register mark alines with the register mark or index M formed on the straight axial edge of the plate P when the plate is located in accurate axial position on the saddle. By this arrangement the plate may be accurately located both axially and circumferentially on the saddle without forming axial locating notches in the plate.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

In preparing a set of plates for producing a multi-color image, the plates are cast in a mold in which each casting matrix is secured in predetermined position. In order to insure that all the plates in the series accurately register in the printing operation, the matrices for producing these plates are registered in exact relation to one another by means of register racks well known to those skilled in the art, and a preferred form is disclosed in the United States Patent No. 2,011,584. The key matrix is squared in the rack by means of marks accurately located on the matrix and wires stretched at right angles across the rack frame so that the point of intersection of the cross wires indicate the approximate center of the matrix. A plurality of adjustable needle points are then moved to registration with se-

lected portions of the image appearing on the matrix, and with the needle points in this position, the trimming points of the matrix are indicated or cut by the rack. The key matrix is then moved, and with the needle points remaining in the position to which they were originally adjusted, the remaining matrices for producing other plates of the series are positioned one at a time in the rack with the selected portion of the image located at the needle point, so that each matrix is located in the rack in exactly the same position as the key matrix to insure that all the plates are cast with their image producing portions located in accurate registering relation with each other. Suitable register indicating marks, as disclosed in this application, are formed in the matrix, and these marks are located with relation to a determined point located at or near the center of the matrix. In casting the plate these marks are formed on each plate, and, are, of course, located with relation to a point located at or near the center of the plate.

In producing printing plates attempts are made to produce each plate, in a series of plates, for printing an image in multi-color, exactly the same size as the remaining plates in the series. It is not always possible, however, to produce all the plates in a series exactly the same size owing to temperature changes, variation in casting shrinkage, and other causes well known to those skilled in the art. Referring to diagrammatic Figure 18 of the drawings, there are depicted two plates in superposed relation with the uppermost plate shown smaller than the lower plate and the inadvertent difference in size of the plates being greatly exaggerated. A distance representing the difference in transverse dimensions of the two plates is indicated at T, and the difference in longitudinal dimensions of the two plates is indicated at L. These plates prior to the margin trimming operation have register marks cast thereon in conformity with the existent practice and located with relation to the upper and left edges of the plates, and, for sake of simplicity, each plate has five circular images shown thereon, as indicated by the reference characters 1, 2, 3, 4, and 5. The images 1, 5 and 3, owing to the difference in transverse dimensions of the two plates, are offset transversely half the distance indicated at T, and the images 4 are offset transversely a distance approximately equal to the distance T. Inasmuch as the images 2 are located adjacent the top edges of the plate they are not offset transversely any appreciable distance. The images 2, 5 and 4 are offset longitudinally a distance equal to half the distance L and the images 3 are offset longitudinally a distance equal approximately to the longitudinal distance L. Thus it is seen that the images 5 located at the centers of the plates are offset both longitudinally and transversely a distance equal to half the distances T and L, and the images 4 are offset transversely a distance approximately equal to the distance T, and the images 3 are offset longitudinally a distance equal approximately to the longitudinal distance L. From the foregoing it is manifest that when the register marks are located with relation to an edge or edges of the plate any inaccuracy in the different plates will result in offsetting the images which are located away from the register edges a distance equal to the difference in the sizes of the plates.

In Figure 19, there are depicted two plates of different sizes positioned in superposed relation

and the difference in the sizes of these plates being the same as indicated in Figure 18. In the plates depicted in Figure 19, however, the register marks are located with relation to a determined point located at or near the center of each plate, consequently, the center images 5 of the two plates are in accurate alinement or register, and the images 1, 2, 3 and 4, which are positioned remotely from the plate center, are offset only 5 half the distance of the transverse difference T the longitudinal difference L in sizes of the two plates. Thus it is seen that in employing applicant's method of locating the register marks with relation to a point located at or near the center of the image producing portion of each plate, that the difference in size of the separate plates employed in printing the same image will result in offsetting the superposed color or image component only half the distance of an offset that 10 would be produced by plates of similar difference in size and having their register marks located with relation to the edge or edges of the plate.

Having thus described my invention, what I claim is:

1. The method of finishing a plurality of printing plates to produce an image in multicolor, which consists in producing on each plate a plurality of register marks accurately located with relation to a determined point located at or near 20 the center of the plate, and trimming the margins of the plate along lines located with relation to the register marks and consequently the said point so that all the plates are exactly the same size and the images thereon located in all directions from said point to have the same relation to the edges of the plate and the said point.

2. The method of finishing a plurality of printing plates to produce an image in multicolor, which consists in producing on each plate a plurality of register marks accurately located with relation to a determined point located at or near 25 the center of the plate, forming locating notches in each plate positioned with relation to the register marks and the said point, bending each plate to arcuate form with its locating notches in its axial margins, and removing the axial and arcuate margins of each plate at points located with relation to the register marks and locating notches and consequently the said point so that 30 all plates are exactly the same size and the images thereon located in all directions from said points to have the same relation to the said points and edges of all the plates.

3. The method of finishing a set of printing plates to produce a common image in a plurality of colors, which consists in producing a plurality of register marks on each plate accurately located with relation to a determined point located at or near the center of the plate, and trimming 35 the margins of each plate along lines located with relation to the said point so that all plates in the set are the same size and the images thereon are located in all directions away from said point and bear the same relation to the said points and edges of all the plates.

4. The method of finishing printing plates for printing cylinders, which consists in producing a plurality of register marks on each plate located with relation to a determined point located 40 at or near the center of the plate, bending the plate to arcuate form, and removing the axial and arcuate margins from the plate along lines located with relation to the register marks and consequently the said point so that components of the matter appearing on the plate are located

5 accurately relative to said points in all directions therefrom.

5. The method of finishing printing plates for printing cylinders, which consists in producing a plurality of register marks on each plate accurately located with relation to a determined point located at or near the center of the plate, forming locating notches in opposed margins of the plate and positioned with relation to the register marks and said point, bending the plate to 10 arcuate form with the locating notches positioned in the straight axial margins of the plate, and removing the axial and arcuate margins of the plate at points located with relation to the register marks and locating notches and consequently 15 the said point so that components of the matter appearing on the plate are located in all directions from said point accurately relative to the said point and edges of the plate.

6. The method of finishing a printing plate 20 having a marginal area and an image-bearing area, which consists in marking the marginal area of the plate with a plurality of indices accurately located with relation to a determined point located at or near the center of the image-bearing area, and trimming the marginal area from the plate along lines located with relation to the indices and consequently the said point so that components of the image are located in all 25 directions away from said point.

7. The method of finishing a printing plate having a marginal area and an image-bearing area, which consists in marking the marginal area of the plate with a plurality of indices located with relation to a determined point located 30 at or near the center of the image-bearing area, bending the plate to semi-cylindrical form, and trimming the marginal area from the plate along lines located with relation to the indices and consequently the said point.

8. The method of finishing a printing plate having a marginal area and an image-bearing area, which consists in marking the marginal area of the plate with a plurality of indices located with relation to a determined point located 35 at or near the center of the image-bearing area, cutting register notches in opposed margins of the plate at points located with relation to the indices and consequently the said point, bending the plate to semi-cylindrical form so that the 40 notches are positioned in the straight axial margins of the plate, and trimming the marginal edges from the plate along lines located with relation to the register notches and the indices and consequently the said point of the finished 45 plate.

9. The method of finishing a set of printing plates to produce a common subject in multicolor, which consists in marking the marginal portions of each plate of the set with a plurality 50 of indices accurately located with relation to a determined point at or near the center of the image-bearing portion of the plate, and trimming the marginal portions from the plate along lines located with relation to the indices and consequently the said point of the plate so that the components of the image on each finished plate are located in all directions away from said point and bear the same positional relation to the said 55 points and edges of the plate as the images on all the plates of the set bear to the said points and edges.

10. The method of finishing a set of printing plates to produce a common subject in multicolor, which consists in marking the marginal 60

- portion of each plate of the set with a plurality of indices accurately located with relation to a determined point located at or near the center of the image-bearing portion of the plate, bending each plate to semi-cylindrical form having straight axial margins and arcuate circumferential margins, and trimming the axial and circumferential margins from each plate along lines located with relation to the indices and consequently the said point so that the image on each finished plate bears the same positional relation to the said point and its edges as the images on all the plates of the set bear to the said points and edges.
11. The method of finishing a set of printing plates to produce a common subject in multi-color, which consists in marking the marginal portion of each plate of the set with a plurality of indices accurately located with relation to a determined point located at or near the center of the image-bearing portion of the plate, cutting register notches in opposed margins of each plate at points located with relation to the indices and consequently the said point, bending each plate to semi-cylindrical form having straight axial margins and arcuate circumferential margins with the register notches positioned in the straight axial margins, and trimming the axial and circumferential margins from each plate along lines located with relation to the indices and register notches and consequently the said point so that the image on each plate bears the same positional relation to the said point and edges as the images on all the plates of the set bear to the said points and edges.
12. Apparatus for finishing a printing plate marked with a plurality of register indices accurately located with relation to a determined point located at or near the center of the plate, including means for accurately trimming the margins of the plate along lines located with relation to the register indices and consequently the said point so that matter on the finished plate is accurately located relative to the said point and edges of the plate.
13. Apparatus for finishing a printing plate marked with a plurality of register indices accurately located with relation to a determined point located at or near the center of the plate, including means for bending the plate to semi-cylindrical form, and means for accurately trimming the straight axial margins and arcuate margins of the plate along lines located with relation to the register indices and consequently the said point so that matter on the finished plate is accurately located relative to the said point and its axial and arcuate edges.
14. Apparatus for finishing a printing plate marked with a plurality of register indices accurately located with relation to a determined point located at or near the center of the plate, including means for notching opposed margins of the plate at points located with relation to the said point, means for bending the plate to semi-cylindrical form so that its notches are located in each straight axial margin of the plate, means for accurately trimming the straight axial and arcuate margins of the plate along lines located with relation to the register indices and the notches and consequently the said point so that matter on the finished plate is accurately located relative to the said point and its axial and arcuate edges.
15. Apparatus for finishing a printing plate marked with a plurality of register indices ac-

curately located with relation to a determined point located at or near the center of the plate, including means for accurately notching the opposed margins of the plate at points located with relation to the said point, plate-bending means having instrumentalities for engaging the notches to locate the plate thereon so that the plate is bent to semi-cylindrical form with the notches located in the straight axial margins of the plate, plate-trimming means having instrumentalities for engaging the notches to accurately locate the plate thereon so that the straight axial margins and arcuate margins of the semi-cylindrical plate are accurately trimmed along lines located with relation to the register indices and notches and consequently the said point so that matter on the finished plate is accurately located relative to the said point and its axial and arcuate edges.

16. Apparatus for finishing a printing plate marked with a plurality of register indices accurately located with relation to a determined point located at or near the center of the plate, including means for accurately notching opposed margins of the plate at points located with relation to the said point, plate bending means having instrumentalities for engaging the notches to locate the plate therein so that the plate is bent to semi-cylindrical form with the notches located in the straight axial margins of the plate, plate-trimming means having instrumentalities for engaging the notches to locate the plate thereon so that the straight axial margins and arcuate margins of the semi-cylindrical plate are accurately trimmed to produce beveled edges located with relation to the register indices and notches and consequently the said point so that matter on the finished plate is accurately located relative to the said point and its beveled axial and arcuate edges.

17. Apparatus employed in finishing printing plates having register indices marked thereon, including a horizontally disposed vertically movable plate supporting table, means for adjustably securing a plate on the table in a position determined with relation to the register indices on the plate, opposed rotary cutters operably positioned adjacent the table in predetermined relation thereto, means for vertically moving the table to thereby move the plate into engagement with the cutter whereby notches are cut in the opposed edges of the plate at points accurately located relative to the register indices.

18. Apparatus employed in finishing printing plates having register indices marked thereon, including a vertically movable plate supporting table, means for adjustably securing a plate on the table in a position determined with relation to the register indices on the plate, opposed rotary cutters operably positioned adjacent the table in predetermined relation thereto, means for vertically moving the table to thereby move the plate into engagement with the cutters whereby notches are cut in the opposed edges of the plate at points accurately located relative to the register indices, and means automatically operable by the movement of the table for shielding the cutters during their cutting operation.

19. Apparatus employed in finishing printing plates having register indices marked thereon, including a horizontally disposed plate supporting table, means for adjustably securing a plate on the table in a position determined with relation to the register indices marked on the plate, opposed power-driven rotary cutters operably lo-

cated below the normal position of the table adjacent opposed edges thereof, manually operable means for moving the table downwardly past the cutters thereby moving the plate into engagement with the cutters to cut register notches in opposed edges of the plate at points accurately located with relation to the register indices on the plate, the table and plate being maintained in substantially horizontal position throughout its movement.

20. Apparatus employed in finishing printing plates having register indices marked thereon, including a horizontally disposed plate supporting table, sighting members accurately located with respect to determined points on the table, each sighting member having a sighting index, means for adjusting a plate on the table and for securing it in a position determined by the accurate alinement of the sighting index of each sighting device with the selected register index on the plate, opposed power-driven rotary cutters operably located below the normal position of the table adjacent spaced edges thereof, manually operable means for moving the table downwardly past the cutters thereby moving the plate into engagement with the cutters to cut register notches in the opposed edges of the plate at points accurately located with relation to the register indices on the plate, the table and plate being maintained in substantially horizontal position throughout its movement.

21. Apparatus employed in finishing printing plates having register indices marked thereon, including means for forming notches in the opposed edges of a plate at points accurately located with relation to the register indices, a bendable plate holder constructed and arranged to receive a plate therein and having marginal flanges, locating fingers carried by the plate holder to engage the notches of the plate to accurately locate the plate in the holder, between the flanges, and cooperating bending rollers to bend the plate to semi-cylindrical form while in its holder so that the notches are positioned in the straight axial edges of the semi-cylindrical plate.

22. Apparatus employed in finishing printing plates having register indices formed in the opposed edges thereof, including a bendable plate holder, a fixed stop member positioned in the plate holder, a yieldable stop member operably positioned in the plate holder, locating fingers extending from the said plate holders and adapted to engage the plate notches to accurately locate the plate in the holder, and bending rollers cooperating to bend the plate to semi-cylindrical form while in its holder so that the notches are positioned in the straight axial edges of the plate, the yieldable stop members yielding to permit elongation of the plate during its bending operation.

23. Apparatus employed in finishing semi-cylindrical printing plates having register indices marked thereon, including an arcuate plate-supporting saddle, sighting members having sighting indices and located at predetermined points with relation to the saddle, means for circumferentially moving the plate on the saddle so that the register indices marked on the plate accurately aline with the sighting indices of the sighting members, means for clamping the plate on the saddle, and means for trimming the straight axial and arcuate edges of the plate while clamped in accurately adjusted position on the saddle thereby producing a plate of ac-

curate dimensions with its image located in definite relation to all edges of the plate.

24. Apparatus employed in finishing semi-cylindrical printing plates having register indices marked thereon accurately located with relation to a determined point located at or near the center of the plate, including a plate-supporting saddle, sighting members having sighting indices and located at predetermined points with relation to the saddle, means for adjusting a plate on the saddle so that the register indices marked on the plate accurately aline with the sighting indices of the sighting members, means for clamping the plate on the saddle, and means for trimming the straight axial and arcuate edges of the plate while clamped in accurately adjusted position on the saddle thereby producing a plate of accurate dimensions with its image located in definite relation to all edges of the plate and the said point.

25. Apparatus employed in finishing semi-cylindrical printing plates having register indices marked thereon relative to the center of the plate and register notches formed in the straight axial edges thereof at points located with respect to the indices, including a plate-supporting saddle, a sighting member having a sighting index and located at a point predetermined with relation to the saddle, means for engaging the notches of a plate to locate the plate in accurate axial relation on the saddle, means for circumferentially adjusting the plate on the saddle so that the register index of the sighting member accurately alines with a register index marked on the plate thereby accurately positioning the plate in predetermined position on the saddle, and means for trimming the straight axial and arcuate edges of the plate while positioned on the saddle thereby producing a plate of accurate dimensions having its edges located in definite relation to its center.

26. Apparatus employed in finishing a semi-cylindrical printing plate having register indices marked thereon relative to the center of the plate and register notches formed in the straight axial edges thereof at points located with respect to the indices, including a plate-supporting saddle, a sighting member having a sighting index and located at a point predetermined with relation to the saddle, manually operable means for engaging the plate notches to locate the plate in accurate axial relation on the saddle, manually operable means cooperating with the said notch-engaging means for adjusting the plate circumferentially on the saddle until the register index of the sighting member accurately alines with a register index marked on the plate to accurately locate the plate in predetermined position on the saddle, and means for trimming the straight axial and arcuate edges of the plate while positioned on the saddle thereby producing a plate of accurate dimensions having its edges located in definite relation to its center.

27. Apparatus employed in finishing a semi-cylindrical printing plate having register indices marked thereon relative to the center of the plate and register notches formed in the straight axial edges thereof at points located with respect to the indices, including an arcuate plate-supporting saddle, a sighting member having a sighting index and located at a point predetermined with relation to the saddle, manually operable means for engaging the notches to locate the plate in accurate axial relation on the saddle, manually operable means cooperating with the

said notch-engaging means for adjusting the plate circumferentially on the saddle so that the register index of the sighting member accurately alines with a register index marked on the plate thereby accurately locating the plate in predetermined axial and circumferential position on the saddle, means for yieldingly holding the plate on the saddle during its circumferential adjusting movement, means for clamping the plate to the saddle after it has been accurately adjusted, and means for trimming the straight axial and arcuate edges of the plate while clamped in predetermined position on the saddle thereby producing a plate of accurate dimensions having its edges located in definite relation to its center.

28. Apparatus employed in finishing semi-cylindrical printing plates having register indices marked thereon and register notches formed in the straight axial edges thereof at point located with respect to the indices, including an arcuate plate-supporting saddle, a sighting member having a sighting index and located at a point predetermined with relation to the saddle, manually operable means for engaging the notches to locate the plate in accurate axial relation on the saddle, manually operable means for adjusting the plate circumferentially on the saddle so that the register index of the sighting member accurately alines with the register index marked on the plate thereby positioning the plate in predetermined position on the saddle, means for clamping the plate in this position on the saddle, rotary cutters movable in an arcuate path of travel to trim the arcuate edges of the plate

while positioned on the saddle, and rotary cutters movable in straight paths of travel to trim the straight axial edges of the plate while clamped on the saddle thereby producing a plate of accurate dimensions.

29. Apparatus employed in finishing semi-cylindrical printing plates having register indices marked thereon relative to the center of the plate and register notches formed in the straight axial edges thereof at points located with respect to the indices, including an arcuate plate-supporting saddle, a sighting member having a sighting index and located at a point predetermined with relation to a given point on a saddle, manually operable means for engaging the notches to locate the plate in accurate axial relation on the saddle, manually operable means for yieldingly holding the plate on the saddle, manually operable means opposing the said yieldable plate holding means for adjusting the plate circumferentially on the saddle so that the register index of the sighting member accurately alines with a register index on the plate thereby accurately positioning the plate in predetermined position on the saddle, manually operable means for securely clamping the plate on the saddle, and power-driven means for trimming the straight axial and arcuate edges of the plate while clamped in predetermined position on the saddle thereby producing a plate of accurate dimensions having its edges located in definite relation to its center.

WILLIAM F. HUCK.
